UNITED STATES PATENT OFFICE.

GEORGE E. BEERS, OF NEW YORK, N. Y.

DESIGN FOR A SOCK OR STOCKING.

43,351.

Specification for Design.

Patented Dec. 24, 1912.

Application filed March 18, 1912. Serial No. 684,629. Term of patent 7 years.

To all whom it may concern:

Be it known that I, GEORGE E. BEERS, a citizen of the United States, residing in the city of New York, borough of Manhattan, in the county and State of New York, have invented a new, original, and ornamental Design for Socks or Stockings, of which the following is a specification, reference being had to the accompanying drawing, forming part thereof.

The figure is a side elevation of an article of hosiery showing my design.

I claim:

The ornamental design for a sock or stocking as shown.

GEORGE E. BEERS.

Witnesses:

IRVING C. LAY,
FRANK G. RAYMOND.
